FREEWHEELING DEVICE

Charles F. Pilcher, St. Louis, Mo.

Application July 17, 1931. Serial No. 551,480

4 Claims. (Cl. 192—48)

The present invention relates to a free wheeling device for motor vehicles and has for one of its important objects to provide, in a manner as hereinafter set forth, a device of this character embodying a novel construction, combination and arrangement of parts, whereby the same may be expeditiously rendered inoperative or operative as desired by the driver of the vehicle.

Another important object of the invention is to provide a free wheeling device of the character set forth which is adapted to be operatively mounted for use on vehicles which are already in use without the necessity of materially altering the same structurally.

Other objects of the invention are to provide a free wheeling device of the character described which will be simple in construction, strong, durable, efficient and reliable in operation and which may be manufactured and installed at low cost.

All of the foregoing and still further objects and advantages of the invention will become apparent from a study of the following specification, taken in connection with the accompanying drawings, wherein like characters of reference designate corresponding parts throughout the several views, and wherein:

Figure 1 is a view in vertical longitudinal section through an embodiment of the invention.

Figure 2 is a view in vertical cross section taken substantially on the line 2—2 of Figure 1 looking in the direction indicated by the arrow.

Figure 3 is a detail view in rear elevation of the traveling clutch member.

Figure 4 is a detail view in front elevation of the portion of the device which is mounted on the drive shaft of the vehicle.

Figure 5 is a view in vertical longitudinal section through a modified form of the invention.

Figure 6 is a detail view in rear elevation of one of the essential portions of the device.

Referring now to the drawings in detail, it will be seen that the reference numeral 1 designates the rear portion of a transmission housing from which the rotatable transmission shaft 2 projects rearwardly. A sleeve 3 is disposed on the projecting end portion of the transmission shaft 2 and is held against rotation by a key 4. Said sleeve has a socketed rear end portion upon which is formed integrally an external flange 5 having a series of openings 6 therein, the purpose of which will be presently set forth. The rear end portion of the transmission shaft 2 is reduced and threaded, as at 7, to receive a retaining nut 8 which extends into the socket of the sleeve 3

and is engaged with said sleeve for retaining the same in position on the transmission shaft 2. A cotter pin 9 extends transversely through the retaining nut 8 and the reduced threaded portion 7 of the transmission shaft 2 for locking said retaining nut on said transmission shaft.

A substantially cylindrical block 10 is fixed in any suitable manner, as by welding or by bolts to the rear face of the flange 5 and said block is provided with passages 11 which register with the openings 6 of the flange 5. Extending rearwardly from the cylindrical block 10 is an annular flange 12 which constitutes a cylinder. The block 10 is recessed in its forward portion for the reception of the rear portion of the sleeve 3 and the nut 8. A spirally threaded shaft 13 extends rearwardly from the cylindrical block 10, said shaft 13 being integral with the block and terminating in a reduced, threaded shank 14.

A bushing 15 is threaded on the shank 14 and secured thereon by a cotter pin 16 extending transversely through the rear end portion of the bushing and the shank. A clutch member 17 is rotatably mounted on the bushing 15 and retained against rearward movement thereon by an external flange 18 formed integrally on a rear portion of the bushing. The clutch member 17 is bolted, as at 19, on the forward end of the drive shaft 20 of the vehicle. The clutch member 17 is mounted for rotation in the cylinder 12 and is provided with a series of sockets 21 extending thereto from its forward end and adapted to be brought into registry with the openings 6 and the passages 11 when the free wheeling device is to be rendered inoperative, as will be more fully hereinafter set forth.

The forward portion of the clutch member 17 is chambered, as at 22, for the reception of a longitudinally movable clutch member 23 which is threadedly mounted on the spirally threaded shaft 13. The clutch member 23 is peripherally grooved for the reception of an expandable split ring 24 which is adapted for frictional engagement with the periphery of the chamber 22. A pin 25 is threaded into the clutch member 23 and is provided with a reduced free end portion disposed between the ends of the ring 24 for retaining said ring against rotary movement relative to the clutch member 23. An expander 26 is disposed in the channel of the clutch member 23 beneath the split ring 24 for yieldingly urging said split ring outwardly against the clutch member 17. The rear face of the clutch member 23 is provided with a circular series of sockets 27 for the reception of the pins 28 in the clutch member

17 for positively locking the clutch members 17 and 23 together.

The reference numeral 29 designates a ring which is mounted for longitudinal sliding movement on the outer periphery of the flange 5, the cylindrical block 10 and the cylinder 12. Said ring extends forwardly beyond the flange 5. The ring 29 is provided with a pair of circumferentially extending flanges 30 which define a channel or groove in which the lower end of a hand lever 31 is disposed for operatively connecting said hand lever to the ring 29. The hand lever 31 is mounted for swinging movement in a vertical plane on a suitable supporting bracket 32. The hand lever 31 is provided with a knob 33 on its upper end. Of course, the lever 31 extends upwardly into the body of the vehicle within convenient reach of the operator of said vehicle. The inner periphery of the ring 29 is provided with a pair of circumferentially extending grooves 34 for the reception of the spring pressed detents 35 which are slidably mounted in the cylindrical block 10.

Rods 36 are mounted slidably in the openings 6 and the passages 11 of the flange 5 and block 10, respectively, for engagement in the sockets 21 of the clutch member 17. The forward end portions of the rods 36 have formed integrally therewith the lateral heads 37 which are secured to the forward portion of the ring 29 by bolts 38. In this manner, the rods 36 are connected to the ring 29 for actuation thereby.

In use, when the direction of power is from the transmission shaft 2 to the drive shaft 20 of the vehicle, the frictional engagement of the ring 24 with the clutch member 17 will cause the clutch member 23 to be threaded rearwardly on the spirally threaded shaft 13 until the pins 28 engage in the sockets 27 and in this manner a positive drive is had from the transmission shaft to the drive shaft. Should the direction of power be reversed, or be from the drive shaft 20 toward the transmission shaft 2, the clutch member 17 will actuate the clutch member 23 through the medium of the friction ring 24, in a manner to thread said clutch member 23 forwardly on the spirally threaded shaft 13, thus disengaging the sockets 27 from the pins 28 and permitting rotation of the drive shaft 20 at greater speed than the transmission shaft 2. When it is desired to lock the drive shaft 20 to the transmission shaft 2 against independent rotation at all times, this is accomplished by actuating the lever 31 manually to shift the ring 29 rearwardly and engage the rods 36 in the sockets 21 of the clutch member 17 and positive drive or connection is thus provided.

In the embodiment of the invention illustrated in Figure 5 of the drawings, the free wheeling device is built into the transmission of the vehicle and the arrangement of the parts is substantially reversed as compared with the form of the invention illustrated in Figure 1. In addition, the block 10 has one end formed to provide a female clutch member 40 for operative engagement by a male clutch member 41 which is splined on the transmission shaft 2. A hand lever 42 is operatively engaged with the clutch member 41 for shifting the same on the transmission shaft 2 into and out of engagement with the clutch member 40.

It is believed that the many advantages of a free wheeling device in accordance with this invention will be readily understood, and although the preferred embodiment of the invention is as illustrated and described, it is to be understood

that changes in the details of construction and in the combination and arrangement of parts may be resorted to which will fall within the scope of the invention as claimed.

What is claimed is:—

1. A free wheeling device for motor vehicles comprising a sleeve fixed on the transmission shaft of the vehicle, a flange on the sleeve, a block fixed on the flange, said block and flange having aligned openings therein, a cylinder formed integrally with the block and extending rearwardly therefrom, a spirally threaded shaft extending rearwardly from the block and disposed centrally in the cylinder, a reduced threaded shank on the free end of the spirally threaded shaft, a clutch member rotatably mounted on the threaded shank, said clutch member having sockets therein for registry with the openings in the block and the flange, said clutch member being rotatable in the cylinder and having the drive shaft of the vehicle secured thereto, a clutch member threaded for operation on the spirally threaded shaft and operable within the first named clutch member, frictional means operatively connecting the second named clutch member to the first named clutch member for actuation thereby, the second named clutch member having a plurality of sockets therein, and pins on the first named clutch member engageable in the sockets for positively connecting the clutch members together when the second named clutch member is moved rearwardly on the spirally threaded shaft.

2. A free wheeling device for motor vehicles comprising a sleeve fixed on the transmission shaft of the vehicle, a flange on the sleeve, a block fixed on the flange, said block and flange having aligned openings therein, a cylinder formed integrally with the block and extending rearwardly therefrom, a spirally threaded shaft extending rearwardly from the block and disposed centrally in the cylinder, a reduced threaded shank on the free end of the spirally threaded shaft, a clutch member rotatably mounted on the threaded shank, said clutch member having sockets therein for registry with the openings in the block and the flange, said clutch member being rotatable in the cylinder and having the drive shaft of the vehicle secured thereto, a clutch member threaded for operation on the spirally threaded shaft and operable within the first named clutch member, frictional means operatively connecting the second named clutch member to the first named clutch member for actuation thereby, the second named clutch member having a plurality of sockets therein, and pins on the first named clutch member engageable in the sockets for positively connecting the clutch members together when the second named clutch member is moved rearwardly on the spirally threaded shaft, a ring encircling the flange, the block and the cylinder for longitudinal movement thereon, means operatively connected to the ring for manually shifting the same, means engageable with the ring for releasably securing the same in shifted position, and means mounted on the ring and engageable with the first named clutch member for positively locking said first named clutch member to the flange for actuation thereby.

3. A free wheeling device for motor vehicles comprising a sleeve fixed on the transmission shaft of the vehicle, a flange on the sleeve, a block fixed on the flange, said block and flange having aligned openings therein, a cylinder formed integrally with the block and extend-

ing rearwardly therefrom, a spirally threaded shaft extending rearwardly from the block and disposed centrally in the cylinder, a reduced threaded shank on the free end of the spirally threaded shaft, a clutch member rotatably mounted on the threaded shank, said clutch member having sockets therein for registry with the openings in the block and the flange, said clutch member being rotatable in the cylinder and having the drive shaft of the vehicle secured thereto, a clutch member threaded for operation on the spirally threaded shaft and operable within the first named clutch member, frictional means operatively connecting the second named clutch member to the first named clutch member for actuation thereby, the second named clutch member having a plurality of sockets therein, and pins on the first named clutch member engageable in the sockets for positively connecting the clutch members together when the second named clutch member is moved rearwardly on the spirally threaded shaft, a ring encircling the flange, the block and the cylinder for longitudinal movement thereon, means operatively connected to the ring for manually shifting the same, means engageable with the ring for releasably securing the same in shifted position, and means mounted on the ring and engageable with the first named

clutch member for positively locking said first named clutch member to the flange for actuation thereby, the last named means including rods disposed slidably in the passages in the flange and in the block and engageable in the sockets of the first named clutch member, said rods being connected to the ring for actuation thereby.

4. In a free wheeling device, a member having a recess therein, a clutch member located in the recess, one of said members having sockets therein and the other member having projections thereon for engaging the sockets when the clutch member has been moved to a certain position, a member including a spirally threaded shaft and said clutch member having a spirally threaded bore through which the shaft passes, said clutch member having an annular groove in its periphery, a split friction ring located in the groove, expanding means located in the groove for forcing the ring outwardly against portions of the wall of the recess, a projection on the clutch member engaging a part of the ring for moving the ring with the clutch member, a driven shaft connected with the first mentioned member and a drive shaft connected with the member carrying the spirally threaded shaft.
